CASING FOR A PORTABLE ELECTRIC ICE CRUSHER

Foster L. Talge, Kansas City, Mo., and Sheldon M. Rutter, Lake Forest, Ill., assignors to John C. Hockery, Kansas City, Mo., as trustee

Application June 6, 1956, Serial No. 41,790

Term of patent 14 years

(Cl. D89—1)

Fig. 1 is a perspective view of a casing for a portable electric ice crusher embodying our new design; and

Fig. 2 is a perspective view showing the opposite side and end of same.

We claim:

The ornamental design for a casing for a portable electric ice crusher, as shown.
